UNITED STATES PATENT OFFICE.

JULIUS E. SCHMIDT, OF ST. PAUL, MINNESOTA.

DRIVING-MITT.

SPECIFICATION forming part of Letters Patent No. 254,164, dated February 28, 1882.

Application filed January 3, 1882. (No model.)

To all whom it may concern:

Be it known that I, JULIUS E. SCHMIDT, a citizen of the United States, and a resident of St. Paul, Ramsey county, Minnesota, have 5 made certain new and useful Improvements in Driving-Mitts, of which the following is a specification.

This invention relates to mittens or hand-protectors used in driving horses in cold or 10 stormy weather; and it consists in mittens having straps or loops connected to or forming part of the driving-reins secured within them, whereby the hands of the driver are protected, as hereinafter shown.

15 In the drawings, Figure 1 is a sectional side view of one of the mittens attached to a rein, and Fig. 2 is a rear view of the same.

A is a mitten or hood, formed usually of two thicknesses of fur, one inside and one outside, 20 and with an extra thickness at B to clasp the arms or wrists more tightly and prevent cold air entering.

C is a leather strap or loop passing through the front end of the mitt and firmly secured 25 thereto. The loop C may either form part of the reins D or be attached to them by the

usual metal clasps, E. By this means the driver is enabled to grasp the reins with his bare hands or with only the ordinary driving-gloves in the coldest weather without being 30 affected by the cold.

These mitts will be found especially useful in driving spirited horses, as the hands will always be in condition to handle the reins in all emergencies.

35 The loop C may be continued backward in the form of one strap, as shown by dotted lines F in Fig. 1, and attached to the reins D again, if desired, to still further increase its efficiency.

What I claim as new is—

40 As a new article of manufacture, a driving-mitt having a strap or loop fixed therein, said strap or loop adapted to be attached to or form part of the driving-reins, substantially as set forth.

45 In testimony whereof I have hereunto set my hand in the presence of two subscribing witnesses.

JULIUS E. SCHMIDT.
